UNITED STATES PATENT OFFICE.

VERONIKA KRASMAUSKIS, OF CHICAGO, ILLINOIS.

HAIR-DRESSING ATTACHMENT.

1,351,427.

Specification of Letters Patent. Patented Aug. 31, 1920.

Application filed March 1, 1920. Serial No. 362,225.

To all whom it may concern:

Be it known that I, VERONIKA KRASMAUSKIS, a citizen of the United States, residing at Chicago, in the county of Cook and State 5 of Illinois, have invented certain new and useful Improvements in Hair-Dressing Attachments, of which the following is a full, clear, concise, and exact description, reference being had to the accompanying drawings, forming a part of this specification.

My invention relates to hair dressing attachment and particularly to an attachment for forming artificial side or ear puffs. The article of my invention consists of two 15 switches of hair connected together by a cord or wire which wire is crossed over the head to support the switches at the side of the head, so that when the puffs are formed up from the switches they will be in the proper 20 position.

My improved invention is shown on the accompanying drawings and its use illustrated. On the drawings—

Figure 1 shows the device of the invention,

Fig. 2 shows it applied to a head, one of the switches being made up into a puff, and

Fig. 3 shows a separable switch connecting wire.

The device consists of two switches 1 and 2 of hair suitably bound together at X, the ends of a connecting wire or cord 3 being secured to the switches by the binding X, or otherwise. The device is applied to the head 35 as shown in Fig. 2, the connecting wire resting on the scalp and being of such length as to bring the switches in proper position that when made up into puffs, such puffs will be located as desired. Fig. 2 shows one of the 40 switches made up into a puff 4. The wire can be readily fastened in place by means of hair pins and the puffs can be likewise fastened.

As it may be desirable to apply the puffs 45 after the natural hair has been dressed, or to take off the side puffs without disturbing

the natural hair dressing, I preferably break the wire so that the ends can be inserted along the scalp under the hair without disturbing the natural hair dress, and I provide 50 suitable clasp mechanism for securing the inserted ends together. As shown in Fig. 3, one section of the wire has the socket member 5 of an ordinary connecting clasp secured thereto while the other wire has the 55 V-shaped clip member 6 secured thereto, the clip when inserted in the socket holding the wire ends together. As it is undesirable to have the clasp appear at the hair parting line the clasps may be given different locations in different attachments. In some of these attachments the clasps could appear at either side so as to be away from the center parting line, and in other devices it could be at the center of the wire so as to be away 60 from the parting line at the side of the head. Thus by having the connecting wire in sections and the clasp mechanism appearing at different places in different devices the form desired can be purchased and then worn 65 without showing the clasp mechanism at the hair parting line. The wire also affords a convenient means for supporting ribbon or other hair ornaments. The puffs can be made up either before or after application of the device to the head.

Having described my invention, I claim as follows:

A hair dressing attachment comprising hair switches, a wire extending from the 80 end of each switch, and clasp members at the ends of said wires for securing them together, the wires when secured together forming a support across the head for said switches to hold in place on the head side 85 puffs or other hair dressing forms made up from the switches.

In witness whereof, I hereunto subscribe my name this 25th day of February, A. D., 1920.

VERONIKA KRASMAUSKIS.
